US00D853492S

(12) **United States Design Patent** (10) Patent No.: **US D853,492 S**
Kihl et al. (45) Date of Patent: ** Jul. 9, 2019

(54) **DIGITAL SIGNAGE**

(71) Applicant: **LG ELECTRONICS INC.**, Seoul (KR)

(72) Inventors: **Hewon Kihl**, Seoul (KR); **Areum Kwon**, Seoul (KR); **Hongseok Kim**, Seoul (KR); **Sechang Park**, Seoul (KR); **Sangwon Yoon**, Seoul (KR); **Yongho Lee**, Seoul (KR)

(73) Assignee: **LG ELECTRONICS INC.**, Seoul (KR)

(**) Term: **15 Years**

(21) Appl. No.: **35/504,804**

(22) Filed: **Oct. 27, 2017**

(80) **Hague Agreement Data**

Int. Filing Date: **Oct. 27, 2017**

Int. Reg. No.: **DM/098277**

Int. Reg. Date: **Oct. 27, 2017**

Int. Reg. Pub. Date: **Apr. 27, 2018**

(30) **Foreign Application Priority Data**

Oct. 18, 2017 (KR) 30-2017-0048415
